(57) **CLAIM**

The ornamental design for augmented reality glasses, as shown and described.

DESCRIPTION

FIG. 1 is an upper-front-left perspective view of augmented reality glasses according to the present invention;

FIG. 2 is an upper-rear perspective view of the augmented reality glasses of FIG. 1;

FIG. 3 is a rear view of the augmented reality glasses of FIG. 1;

FIG. 4 is a front view of the augmented reality glasses of FIG. 1;

FIG. 5 is a right view of the augmented reality glasses of FIG. 1;

FIG. 6 is a left view of the augmented reality glasses of FIG. 1;

FIG. 7 is a top-down view of the augmented reality glasses of FIG. 1; and,

FIG. 8 is a bottom-up view of the augmented reality glasses of FIG. 1.

The broken lines in the drawings are shown for the purpose of illustrating portions of the augmented reality glasses and form no part of the claimed design.

1 Claim, 6 Drawing Sheets
